UNITED STATES PATENT OFFICE.

ALBERT A. ALLINGER, OF RICHMOND HILL, NEW YORK.

FIGURE WHEEL TOY.

Application filed March 10, 1927. Serial No. 174,126.

This invention relates to toys and more particularly to that class of toys adapted to be drawn along the ground and to imitate, by their motion, the performance of a movement 5 by a figure included in the toy.

One object of the present invention is the provision of a doll adapted to be mounted upon the representation of an aquaplane which is carried with a wheeled platform and 10 automatically caused to move in simulation of an aquaplane moving over the surface of the water by the propulsion of the platform. Accordingly, the doll is carried with a board hinged at its rear end to the platform and 15 carrying a cam guide adapted to be displaced in predetermined manner by a cam carried with an axle.

The invention also seeks a toy structure whereby the foregoing object is attained and 20 which shall be practical from the standpoint of ease and cheapness of manufacture and durability in use.

These and other objects of the invention and the means for their attainment will be 25 more apparent from the following detailed description, taken in connection with the accompanying drawings, illustrating a preferred embodiment thereof, in which:

Figure 1 is a view in perspective showing 30 the aquaplaning doll according to this invention.

Figure 2 is a longitudinal vertical sectional view, taken in the plane indicated by the line 2-2 in Figure 1, looking in the direction of 35 the arrows, and showing details of the actuation mechanism whereby the doll and aquaplane is caused to simulate the movement of an actual aquaplane on the water.

Figure 3 is a detail view on the line 3-3 40 of Figure 2 showing the manner of securing a celluloid doll, say, to the aquaplane.

The aquaplaning doll 4 which may conveniently be formed of celluloid, and hence hollow, is shown as clamped by its feet 5 to the 45 aquaplane board 6 by a flat headed screw 7 countersunk in the bottom of the board and passing through an aperture 8 therein for engagement in a hole 9 tapped in a clamp plate 10 which may easily be slipped sideways into 50 slots 11 cut in the sides of the doll's feet 5 to rest upon and clamp the lower surface 12 to the aquaplane 6.

The aquaplane board 6 is shown as hinged

at its rear end as at 14 to a platform 15 which may be of wood or metal and if desired painted or otherwise treated to simulate the waves of a body of water and a cord 16 may be passed through holes 17 at either front corner of the board 6 and through the doll's hands 18 to simulate the usual rope for that purpose found on aquaplanes. This cord may conveniently be tied through the same hole 19 in the platform 6 to which the string 20 is tied by which the platform 6 is drawn over the floor 21 or other surface.

Pairs of wheels 23 are mounted upon the outer ends of front and rear axles 24 and 25 respectively which are journaled in depending brackets 26 which are preferably of metal and formed by bending down and perforating the 65 ends of metallic straps 27 which may then be secured to the platform by the screws 28.

To give the aquaplane board 6 an up and down movement simulating the actual movement of an aquaplane when drawn over the 70 surface of the water, there is secured to the underside of the board 6 as by the screws 30 a metallic guide 31 which is bent first downwardly as at 32 to pass through a slot 33 cut in the platform 15 and then rearwardly to the rear axle 25 as at 34 about which it is curved 75 in an upward direction as at 35 and about a cam 36 carried on the rear axle 25.

Thus as the axle rotates the cam 36 is 80 brought downwardly into engagement with the part 34 of the guide member 31 moving it downwardly but forwardly and thus pushing the board 6 upwardly to swing about the hinge 14 and as the axle 25 continues its rotation the cam 36 is brought into contact with the part 35 of the guide 31 to move it rearwardly and draw the aquaplane board 6 85 downwardly. It will be appreciated that as the axle 25 continues to revolve as the wheeled platform 15 is propelled over the surface 21 90 that the board 6 will be given a continuing up and down movement as the cam 36 repeats the cycle described.

It will thus be seen that an aquaplaning 95 doll is mounted upon a wheeled platform in a rugged structure which is simple and inexpensive to manufacture and which lends itself to effecting the gyrations of the doll in a convenient positive and lifelike manner.

Various modifications may be made in the 100 composition and configuration of the com-

ponent elements going to make up the toy as a whole without departing from the spirit and scope of the invention as delineated in the accompanying claim.

5 What I claim is:—

A toy comprising a platform, a front and a rear axle to support the platform and wheels supporting the axles, a board hinged at its rear end to the platform, a doll mounted on

the board, said platform being formed with 10 an aperture beneath the board, a cam guide secured to the board and extending downwardly and rearwardly and curving upwardly about the rear axle and a cam carried by the rear axle to engage the cam guide. 15

In testimony whereof I affix my signature.

ALBERT A. ALLINGER.
